CASING FOR AN ARTICLE HANDLING MACHINE

John E. Belski, Beverly, and Donald J. T. Hamm, Ipswich,
Mass., assignors to United Shoe Machinery Corpora-
tion, Flemington, N.J., a corporation of New Jersey

Filed Dec. 2, 1960, Ser. No. 63,081

Term of patent 14 years

(Cl. D55—1)

Fig. 1

Fig. 2

Fig. 3

Fig. 4

Fig. 5

FIG. 1 is a perspective view of the front and side of a casing for an article handling machine embodying our new design;

FIG. 2 is a top plan view thereof;

FIG. 3 is a perspective view of the rear and opposite side thereof;

FIG. 4 is a rear elevation thereof; and

FIG. 5 is a side elevation thereof.

We claim:

The ornamental design for a casing for an article handling machine, substantially as shown.
